[57] CLAIM

The ornamental design for a surgical tray for sharp surgical instruments, as shown and described.

DESCRIPTION

FIG. 1 is a top left side perspective view of a surgical tray for sharp surgical instruments, showing my new design, the broken line showing of the surgical instrument being for illustrative purposes only and forming no part of the claimed design;

FIG. 2 is a right side, elevational view thereof, the view from the left side being a mirror image thereof;

FIG. 3 is a top, plan view thereof;

FIG. 4 is an elevational view thereof from the end opposite the handle;

FIG. 5 is a bottom plan view thereof; and,

FIG. 6 is an elevational view thereof from the end with the handle.
